DESIGN FOR A GAME DEVICE

William Francis Drueke, Jr., Grand Rapids, Mich.

Application March 5, 1943, Serial No. 109,673

Term of patent 3½ years

To all whom it may concern:

Be it known that I, William F. Drueke, Jr., a citizen of the United States, residing at Grand Rapids, in the county of Kent and State of Michigan, have invented a new, original, and ornamental Design for a Game Device, of which the following is a specification, reference being had to the accompanying drawing, forming part thereof.

Fig. 1 is a perspective view of a game device showing my new design.

Fig. 2 is a plan view of the same, and
Fig. 3 is a side elevation of the same.

I claim:

The ornamental design for a game device, as shown.

WILLIAM FRANCIS DRUEKE, JR.
